(57) **CLAIM**

The ornamental design for a bag, as shown and described.

DESCRIPTION

FIG. 1 is a top perspective view of a bag showing my new design;

FIG. 2 is a first perspective side view thereof in an open configuration;

FIG. 3 is a second perspective side view thereof opposite the view of FIG. 2;

FIG. 4 is an exploded bottom plan view thereof illustrating the removable components;

FIG. 5 is a rear view thereof;

FIG. 6 is another perspective side view thereof showing removable components; and,

FIG. 7 is another perspective side view thereof showing the removable components.

The broken lines illustrate portions of the bag and form no part of the claimed design.
